United States Patent

Des. 240,545
Patented July 13, 1976

240,545

BANK

Sadayasu Miyazaki, 7-9-10 Tateishi, Katsushika-ku,
Tokyo, Japan

Filed Jan. 6, 1975, Ser. No. 538,864

Term of patent 14 years

Int. Cl. D31—00

U.S. Cl. D34—11 R

FIG. 1

FIG. 2

FIG. 3

FIG. 1 is a front perspective view of a bank showing my new design, the rear perspective view being substantially plain and unornamented;

FIG. 2 is a top plan view thereof; and
FIG. 3 is a bottom plan view thereof.

I claim:

The ornamental design for a bank, as shown and described.
